UNITED STATES PATENT OFFICE.

JOSEPH PARSONS, OF LAKEVILLE, CONNECTICUT.

FIREPLACE HEATING SYSTEM.

1,251,916.

Specification of Letters Patent.

Patented Jan. 1, 1918.

Application filed August 17, 1916. Serial No. 115,371.

To all whom it may concern:

Be it known that I, JOSEPH PARSONS, a citizen of the United States of America, residing at Lakeville, Connecticut, have invented a new and useful Fireplace Heating System, of which the following is a specification.

It is the main object of my invention not only to utilize the direct heat of an open fireplace for heating a room but also to utilize the fire as a means of heating the room at one or more points remote from the fire so as to more uniformly heat the room.

The invention contemplates the use of what may be termed a "fireback" built into the chimney or in the wall or walls of the fireplace. This fireback has an inlet for cold fresh air and an outlet or outlets for hot air, said outlet or outlets discharging into the room remote from the fireplace. The operation depends upon the suction action of the fire in the fireplace by reason of which a current of air is drawn from the room through the fireplace and up the chimney or flue. This suction of air from the room draws air through the fireback where it is heated and discharges it into the room. The suction depends upon the room being closed or closed sufficiently to draw air through the fireback. It is well known that a fireplace will often smoke badly when the windows and doors of the room are closed. My invention by providing for a supply of fresh air to the room prevents such action and improves the action of the fire.

Figure 1, is a vertical sectional view of a construction embodying the improvements of my invention.

Fig. 2, is a fragmentary horizontal section and plan on the plane of the line 2--2 of Fig. 1.

Fig. 3, is a fragmentary vertical sectional view, showing a fireplace with a fireback with a partition dividing it into two parts.

Fig. 4, is a horizontal sectional view of the same on the plane of the line 4--4.

Figs. 5 and 6 are fragmentary vertical sectional views of a fireplace with a fireback provided with two partitions dividing it into three parts, Fig. 5 being a section on the plane of the line 5--5 of Fig. 6 and Fig. 6 being a section on the plane of the line 6--6 of Fig. 5.

Fig. 7, is a fragmentary vertical sectional

view of a construction somewhat similar to Figs. 5 and 6 but showing the air admitted to the fireback from a point remote from the chimney and showing the air discharged from the fireback through a baseboard or wall type of register.

A room of any suitable construction is indicated by the reference numeral 10. The fireplace 11 and chimney or stack 12 may be of any suitable construction adapted to receive the fireback 14. This fireback may be of any suitable material such as cast or sheet metal and is provided with an inlet 15 and an outlet 16. Suitable grilles or registers may be provided for the inlets and outlets such for instance, as the floor register 16 with the usual regulating fans and vanes. The outlet 16 is located at such a point in the room as it is particularly desired to heat, and is connected to the fireback by a flue 17. A damper, such as 18, may conveniently be provided hinged for instance, to the upper edge of the fireback 14 for controlling the draft through the fireplace. A shield such as 19 may be provided above the air inlet 15 to prevent water from running into the fireback.

In the construction shown in Figs. 3 and 4 the fireback 20 is provided with a tortuous passage for the air. This results from the use of a partition 21 which divides the fireback into two passages 20^a, 20^b. In this construction it will be noted that the air inlet 22 is at the lower end of the fireback so that the air first rises and then falls thus preventing the hot air in the fireback from tending to discharge at the top.

In the form shown in Figs. 5 and 6 the fireback 30 is provided with two vertical partitions 31 dividing it into two side parts 30^a, 30^b and the central part 30^c. In this case, the air enters through the two inlets 32, 33 and passes up at the sides and down through the center. In this way the air flowing into the fireback is heated as well as the air flowing out of the fireback. While this construction takes up more width for a given capacity it requires less depth than the form shown in Figs. 3 and 4.

In case the chimney is not located at the outside of the house as for instance, the chimney 40, in Fig. 7, the air may be introduced to the fireback for instance, from an inlet 41 at some convenient point. It will also be obvious that instead of discharging

the warm air through a register in the floor, a side wall or baseboard register such as 42 may be employed.

The construction herein set forth has been found to supply a substantial amount of heat to the room and of a more uniform character than is possible by the ordinary fireplace. Ordinarily of course when a fire is used the doors and windows of the room will be closed to conserve the heat. If the room is at all tight the ordinary fire is very likely to smoke because of lack of air. My invention has been found to provide all the air necessary for the burning of the fire without smoking. If for any reason the additional heat is not required, the register 16 may of course be closed. My improved method of heating by continually supplying fresh air to the room keeps the air in the room in a much better condition than the ordinary fireplace method. The air discharging through the register 16 being warmer than the air in the room adjacent the register naturally rises, while the cooler air around the floor is drawn to the fire and up the chimney. There is thus a continuous circulation of the warm air throughout the room.

What I claim is:—

1. Heating apparatus for a room, comprising a fireplace open to the room and provided with a flue forming an outlet from the room, an air heating chamber disposed in heat receiving relation to the fireplace, said air heating chamber having a fresh air inlet outside the room and provided with an outlet for heated air opening into the room at a lower level than the fireplace and at a point remote from the fireplace to thereby deliver fresh air heated by the fireplace to a point within the room removed from the fireplace, from which point such heated fresh air will traverse the room back to the fireplace and escape through the flue thereof, thereby creating throughout the room a circulation of fresh air heated from the fireplace.

2. Heating apparatus for a room, com-

prising a fireplace open to the room and provided with a flue forming an outlet from the room, an air heating chamber disposed in heat receiving relation to the fireplace, said air heating chamber having a fresh air inlet outside the room and provided with an outlet for heated air opening into the room at a lower level than the fireplace and at a point remote from the fireplace to thereby deliver fresh air heated by the fireplace to a point within the room removed from the fireplace, from which point such heated air will traverse the room back to the fireplace and escape through the flue thereof, thereby creating throughout the room a circulation of fresh air heated from the fireplace, and means controlling the heated air delivered by said air heating chamber to the before mentioned lower remote portion of the room.

3. Heating apparatus for a room, comprising a fireplace opening into the room and provided with an outlet flue, an air heating chamber at the back of said fireplace having a fresh air inlet and a passage extending downwardly therefrom across the back of the fireplace, said air heating chamber having an outlet conduit in communication with said downwardly extending passage and opening into the lower portion of the room at a point remote from the fireplace.

4. Heating apparatus comprising the combination of a room with an open fireplace, and a heating back for the fireplace, said back having an upwardly extending flue and a downwardly extending flue communicating therewith and having a fresh air inlet leading to the lower end of the upwardly extending flue, and a conduit for the heated air leading from the lower end of said downwardly extending flue and discharging heated air into the lower part of the room at a point remote from the fireplace whence said heated air circulates through the room and augments the draft through the fireplace.

JOSEPH PARSONS.
